UNITED STATES PATENT OFFICE

1,967,788

APPARATUS FOR PRODUCING PROFILE METAL ARTICLES

Hugo Seiferth, Dusseldorf-Oberkassel, Germany

Application January 6, 1931, Serial No. 506,965
In Germany February 1, 1930

2 Claims. (Cl. 80—19)

The invention relates to apparatus for producing profile metal articles and more especially metal bars having sharply projecting ribs of considerable height according to my prior Patent No. 5 1,921,486 in which the work piece to which the desired profile is to be given is guided between a roller and a table which wholly or partially comprises the said profile. It has been found that the use in the rolling table of a section of table 10 which bears the complete profile is in many cases very expensive, particularly when the distance apart on the work of the transverse portions of the profile only is altered and when the dimensions differ. Furthermore, it is advantageous for 15 other reasons to improve the table.

According to the invention that part of the rolling table which is formed with the profile is simplified and can be employed for various purposes, if the section of table is sub-divided in such 20 manner that single interchangeable die portions are formed which can be fitted into the section of table, but vary in dimensions.

One construction of apparatus according to the invention is illustrated by way of example in the 25 accompanying drawing.

Figure 1 shows the finished product in longitudinal section.

Figure 2 is a corresponding plan view.

Figure 3 is a longitudinal section through the 30 rolling device the table of which is provided with interchangeable die portions.

Figure 4 shows the section of table with the 35 insertions in plan, and

Figure 5 and 6 are cross-sections taken 40 through the table showing details of the securing means.

The work *a* is formed with transverse projections *b*, *c*, *d*, *e*, *f*, *g*, *f* all of equal height (Figs. 1 and 2). If a duplicate is required, for example, 45 differing from the design shown in the drawing, only in that the projections are of a different height or in that the projections *c* and *g* are at a different angle, it would be necessary to provide another table insertion *x* were there no provision 50 of interchangeable die portions *h*, *i*, *k*, *l*, *m*, *n*, *o*, these insertions enabling changes to be made in the product without involving expensive modifications of the machine, simply by the substitution of the die portions one for another. In Fig. 53 the work piece *a* which is supported by the rollers *w* is pressed by the roll *s* on the rolling table with its die portions and into the transverse grooves of the latter. On the underside of the 55 rolling table, which may be driven in a longitudinal direction by a gear wheel *u*, the counter-pressure roll *t* and the supporting rollers *v* and *v*₁ are arranged. The insertions are held secure longitudinally by wedges, it being sometimes sufficient to provide a wedge *p*, on one side only, the 60 wedge pressing the die portions against a projec-

tion provided on the opposite side. This wedge *p* is held securely in position by headed screws *q*. The insertions are extended outwards laterally (Figures 5 and 6) so that they have a trapezoidal section which fits into the dovetail-section of the 65 table insertion *x* and prevents their rising. By means of clamping members *r* (Figure 6), the longitudinal sides of the die portions may be pressed tightly upon the base of the table insertion *x*, a resilient support being interposed, if necessary. 70

In particular cases, such as when the projections are undercut, it may be advantageous to dispense with special means for fixing the die portions, particularly in the transverse direction. 75 The work will then be removed from the table insertion with the correspondingly sub-divided die portions thereon, and the die portions be removed from the work separately.

What I claim and desire to secure by Letters 80 Patent in the United States is:

1. A device for the production of profile metal bars having sharply projecting transverse ribs of considerable height consisting of a pressure roll, a counter-pressure roll, a rolling table reciprocating between the said rolls, a longitudinal recess in the table, a die insertion in the said recess, a longitudinal recess in the said insertion having a dovetail section, interchangeable die portions in the said recess of the insertion which are partly provided with transverse grooves and have a trapezoidal section, wedges at the end of the die insertions for fastening the die portions, screws for securing the wedges, and supporting rollers for the die table. 85

2. A device for the production of profile metal bars having sharply projecting transverse ribs of considerable height, consisting of a pressure roll, a counter-pressure roll, a rolling table reciprocating between the said rolls, a longitudinal recess in the table, a die insertion in the said recess, a longitudinal recess in the said insertion having an undercut rectangular section, interchangeable die portions of trapezoidal section which are arranged in the said recess of the table insertion and partly provided with transverse grooves, clamping members at the sides of the die portions, wedges at the ends of the recess of the table insertion for securing the die portions in the longitudinal direction, screws for fastening the said wedges, and supporting rollers for the die table. 100
